The ornamental design for a passive EM antenna for an electronic device, as shown and described.

DESCRIPTION

FIG. 1 is a perspective view of a passive EM antenna;
 FIG. 2 is a front view of the passive EM antenna of FIG. 1;
 FIG. 3 is a back view of the passive EM antenna of FIG. 1;
 FIG. 4 is a left side view of the passive EM antenna of FIG. 1;
 FIG. 5 is a right side view of the passive EM antenna of FIG. 1;
 FIG. 6 is a top view of the passive EM antenna of FIG. 1; and,
 FIG. 7 is a bottom view of the passive EM antenna of FIG. 1.
